UNITED STATES PATENT OFFICE.

LLOYD G. COPEMAN, OF FLINT, MICHIGAN, ASSIGNOR TO COPEMAN LABORATORIES COMPANY, OF FLINT, MICHIGAN, A CORPORATION OF MICHIGAN.

REFRIGERATOR.

Application filed May 29, 1924. Serial No. 716,612.

This invention relates to a refrigerator construction and more particularly pertains to the insulation between the inner and outer shell of the refrigerator.

5 Such a construction which involves this form of insulation is well adapted to a construction, in which the inner shell is formed of cast stone and is suitably secured and floated within the outer shell.

10 One of the features is a provision of means whereby the heat insulating material may be pressed between the two shells of the refrigerator, and a binder poured therein, thereby additionally supporting the inner shell in spaced relation with respect to the outer shell.

15 Another feature is the casting of fibrous strips onto the inner shell to which a cover or back plate may be secured, said back plate being also secured to the outer shell, thereby rigidly supporting the inner shell in spaced relation with respect to the outer shell.

In the drawings:

20 Fig. 1 is a vertical section through the refrigerator taken on the line 1—1 of Fig. 2.

Fig. 2 is a horizontal section through the refrigerator taken on the line 2—2 of Fig. 1.

25 Fig. 3 is a vertical section through the refrigerator taken on the line 3—3 of Fig. 2.

Fig. 4 is a detail section taken on the line 4—4 of Fig. 2, showing the fastening means by which the strip is secured to the inner shell and secured to the back plate.

30 Fig. 5 is an enlarged detail showing the insulation structure in detail.

The refrigerator comprises an outer shell *a*, which is preferably formed of a built up structure of fibrous material, such as wood, or it may be moulded stone. This outer shell is provided with an opening *b* at the rear and is provided with a plurality of door openings *c* at the front.

35 Secured to the front wall of the outer shell are a plurality of angle bars *d* which are shown in Fig. 1 as surrounding the door openings *c*. The inner shell *e* is telescoped within the outer shell by inserting the same

40 through the opening at the rear of the outer shell while the outer shell is lying on its face on the floor.

The inner shell is provided with partitions *f* which divide the inner shell into a plurality of chambers. This inner shell is fitted

in between the angle bars *d* and the tension members *g*, which are preferably formed of wide, flexible steel straps secured to the angle bars *d* at a plurality of spaced points. As shown in Fig. 2, these tension members 60 are looped through an opening in the angle bars; the two parts of the strap then being crimped together as at *h* for securely anchoring said tension members to the angle bars. The free end of these flexible straps 65 or tension members are then pulled taut about the inner shell and are secured together as at *i* by clamping the same together with a suitable tool.

I have provided a number of fibrous 70 strips *j*, preferably of wood, which are cast united with the back wall of the inner shell. To accomplish this I first drive a plurality of large headed nails *k* in the strips *j*. They are then inserted in the mould in such 75 a way that when the inner shell is cast the cement will flow about these heads of the nails which project from the strip and thus securely key the strip to the stone work which forms the inner shell. These strips 80 are provided with a plurality of tunnels *m* through which the tension members *g* are passed so that when the said tension members are clamped about the inner shell they 85 will engage said inner shell throughout their entire length, and securely grip the inner shell.

Before inserting the inner shell into the outer shell, I line the outer shell with a relatively thick layer of cork board, designated *n*. In the preferred form of construction, in which the outer shell is formed of a fibrous material, this cork board may be secured in place by nails or other suitable fastening devices, as shown at *o*. After the inner shell has been positioned within the outer shell and secured thereto by the clamping devices above described, I pack the space between the inner and outer shells with cork 90 fragments and then pour in a binder that is a non-conductor of heat, such as pitch, which fills all the crevices existing in the cork fragments, thereby forming a solid wall 95 structure.

This insulating medium formed of cork 100 fragments and a binder is easily handled. The relatively small cork fragments are packed in the space between the inner shell and the cork lining secured to the outer shell in such a way that the fragments contact 105 110

- with each other. The binder, preferably pitch, is poured, after being heated, over these cork fragments, thereby filling the interstices between said cork fragments. This results in practically isolating the binder material in the form of islands as clearly shown in Fig. 5, where the cork fragments are designated *t* and the binder or pitch is designated *u*, and shown as heavily shaded.
10. As a result, this insulating packing when set provides a solid structure in which the contacting cork fragments are tightly bound together by the binder which fills all existing crevices therebetween.
15. This packing becomes rather hard when allowed to set and therefore provides a relatively rigid support for the inner shell, and resists compressive strains so as to prevent the inner shell, which is of a cast material
20. from cracking. Such an insulating medium is well adapted to a refrigerator construction in which the outer shell is formed of cast stone as this packing will reinforce the refrigerator so that the same may resist compressive strains.

I next lay some layers of cork board on top of this inner shell, the said cork board positioned between the fibrous strips *j*. This serves to thoroughly insulate the rear portion 30 of the refrigerator and serves to prevent the conduction of heat from the exterior into the interior of the refrigerator.

I provide a cover plate *s*, which is more commonly termed a back plate, for closing the large opening in the rear of the outer shell. This back plate is fastened down by means of fastening devices *q* to the wooden strips *j* carried by the inner shell. This is shown in Figs. 2 and 4. In addition, the fastening devices *r* secure this back plate to the outer shell, as shown in Fig. 2.

It will be plain from this that the inner shell is securely tied to the outer shell and floated therein by means of these several forms of fastening devices, to wit: tension members which secure the shell to the front wall of the outer shell, the angle bars which support the front edge of the inner shell and the back plate which fastens the rear 50 of the inner shell to the rear part of the outer shell. The insulating material between the outer and the inner shell additionally supports the inner shell at intermediate points.

55. What I claim is:

1. In a container structure, the combination of an outer shell provided with an opening, an inner shell therein and secured thereto in spaced relation, said inner shell provided with a fibrous strip secured thereto, and a back plate fitted in the opening of the outer shell and engaging the outer shell and secured to the fibrous strip secured to the inner shell.
2. In a container structure, the combina-

tion of an outer shell provided with an opening, an inner shell therein and secured thereto in spaced relation, said inner shell provided with a fibrous strip cast-united thereto, and a back plate for closing the opening in the outer shell and secured to both the outer shell and to the fibrous strip carried by the said inner shell.

3. In a container structure, the combination of an outer shell provided with an opening in the rear thereof, the inner shell therein and secured thereto in spaced relation, said inner shell provided with a fibrous strip cast-united to the back wall thereof, and a back plate for closing the opening in the rear of the outer shell and connected to the fibrous strip carried by the back wall of the inner shell.

4. In a container structure, the combination of an outer shell provided with an opening, an inner shell telescoped therein and secured thereto in spaced relation, said inner shell provided with a fibrous strip secured thereto, an insulating medium between said inner and outer shells comprising relatively small fragments of cork and a binder, and a back plate for closing the opening in the outer shell and secured both to the outer shell and to the fibrous strip carried by the inner shell.

5. In a container structure, the combination of an outer shell provided with an opening and having a relatively thick layer of cork board secured to the inside face of the walls of the outer shell, an inner shell 100 within the outer shell and secured thereto in spaced relation, said inner shell provided with a fibrous strip secured thereto, and a back plate fitted in the opening in the outer shell and engaging both the outer shell and secured to the fibrous strip carried by the inner shell for fastening the inner shell in such spaced relation.

6. In a refrigerator construction, the combination of an outer shell provided with an opening at the rear and one or more door openings at the front, said outer shell having secured thereto angle bars which surround said openings, an inner shell telescoped within the outer shell and provided 110 with one or more chambers registering with the door openings in the front of the outer shell, tension members anchored to said angle bars and clamped about the inner shell for securing the said inner shell to the outer shell and floating the inner shell therein in spaced relation with respect to the outer shell, a lining of cork board secured to the walls of the outer shell, relatively small cork fragments packed in between the inner shell and the cork lining, said fragments contacting with each other, a binder poured on said cork fragments to fill up the interstices between the fragments to form a solid insulating wall structure when al-

lowed to set, fibrous strips secured to the back wall of the inner shell, strips of cork board fitted between said fibrous strips for forming an insulated wall at the back of the 5 refrigerator, and a back plate for closing the opening in the rear of the outer shell and secured both to the outer shell and to the fibrous strips carried by said inner shell.

7. In a refrigerator construction, the combination of an outer shell provided with an 10 opening at the rear and one or more door openings at the front, said outer shell having secured thereto angle bars which surround said opening, an inner shell telescoped within the outer shell and provided 15 with one or more chambers registering with the door openings in the front of the outer shell, a tension member anchored to said angle bars and clamped about the inner shell 20 for securing the said inner shell to the outer shell and floating the inner shell therein in spaced relation with respect to the outer shell, relatively small cork fragments packed 25 in between the inner shell and the outer shell, said fragments contacting with each other, a binder poured on said cork fragments to fill up the

interstices between the fragments to form a solid insulating wall structure when allowed 30 to set.

8. In a refrigerator construction, the combination of an outer shell provided with an opening at the rear and one or more door 35 openings at the front, said outer shell having secured thereto angle bars which surround said opening, an inner shell telescoped within the outer shell and provided with one or more chambers registering with the door openings in the front of the outer shell, a tension member anchored to said angle bars and clamped about the inner shell 40 for securing the said inner shell to the outer shell and floating the inner shell therein in spaced relation with respect to the outer shell, relatively small cork fragments packed 45 in between the inner shell and the outer shell, said fragments contacting with each other, a binder poured on said cork fragments to fill up the 50 interstices between the fragments to form a solid insulating wall structure when allowed to set.

In testimony whereof I have affixed my signature.

LLOYD G. COPEMAN.
